Primary Examiner — Karen S Acker*(74) Attorney, Agent, or Firm* — Kimberly-Clark Worldwide, Inc.**(57) CLAIM**

We claim the ornamental design for a patterned tissue product, as shown and described.

DESCRIPTION

The sole FIGURE is a top plan view of a patterned tissue product.

The outer perimeter of broken lines defines the boundaries of the claimed design and forms no part thereof.

The thickness of the patterned tissue product forms no part of the claimed design.
